UNITED STATES PATENT OFFICE.

STANLEY L. GEDNEY, OF MAPLEWOOD, NEW JERSEY.

NECKTIE-HOLDER.

1,121,086.

Specification of Letters Patent. Patented Dec. 15, 1914.

Application filed February 24, 1912. Serial No. 679,791.

To all whom it may concern:

Be it known that I, STANLEY L. GEDNEY, citizen of the United States, residing at Maplewood, in the county of Essex and State of New Jersey, have invented certain new and useful Improvements in Necktie-Holders, of which the following is a specification.

This invention relates to necktie holders. 10 One object is to provide a necktie holder which may be readily applied to the wearer's shirt and necktie to clamp the latter and effectually hold the tie taut.

Another object is to provide a simple, inexpensive, durable and ornamental necktie holder which may be readily disconnected from its application as well as applied for the purposes herein stated.

Another object of my invention is to provide a necktie clasp constructed from a single piece of sheet metal having cut out portions to obtain a clasp of light weight and of skeleton-like formation.

With the above and other objects in view 25 the present invention consists in the combination and arrangement of parts herein-after more fully described, illustrated in the accompanying drawings and more particularly pointed out in the appended claim, it 30 being understood that changes may be made in the form, proportion, size and minor details, without departing from the spirit or sacrificing any of the advantages of the invention as defined by the scope of the appended claim.

In the drawings:—Figure 1 is a front view of a portion of a shirt and collar illustrating a necktie secured to the shirt by my improved holder. Fig. 2 is a plan view. 40 Fig. 3 is a side view. Fig. 4 is a plan view illustrating the material out of which my improved holder is formed.

Referring now more particularly to the accompanying drawings the reference character 45 1 indicates a shirt, 2 a collar, and 3 a necktie.

As will be seen by reference to Fig. 4 my improved holder is preferably stamped out of a single piece of metal or other suitable material and has all of its edges rounded so as to obviate cutting edges as well as to provide for ornamentation. Out of this single piece of material shown in Fig. 4 my improved holder is formed and it is indicated generally by the reference character A the single piece of material being enlarged

at one end, as at 6, and terminating in the long narrow extension, as at 5. The ends of said single piece of material are cut out, as shown, leaving the web 4 intermediate the ends of said piece of material, the said web being disposed preferably slightly off from the center of the single piece of material. At this web 4, the single piece of material is bent upon itself to provide clasping members 5 and 6, each by virtue of the respective cutout portions including spaced parallel side portions connected at their outer ends by bight portions, as shown. The bending of the material at its said web 4 provides an eye 7 resulting in a spring hinge connection between the clasping members.

The clasping member 5 is preferably narrower than the clasping member 6 and preferably of greater length than the latter with the side portions of the clasping member 6 directed laterally intermediate their ends slightly beyond the plane of the side portions of the clasping member 5, whereby 80 intermediate the ends of the clasping members clamping bends or points, as indicated at 8 are provided to effect a firm gripping of the shirt and tie together.

To facilitate application of the holder, it 85 is preferred that the outer ends of the clasping members 5 and 6 be slightly curved as indicated at 9 and 9, respectively, the curvature of both members being in the same direction and forming a throat or mouth by virtue of 90 which the thicknesses of the shirt front and neck tie will not interfere with proper application of the holder.

The web 4 in addition to providing for a substantial hinge connection between the 95 clasping members also provides an enlargement when the eye 7 is formed to accommodate any bulging or ruffling of the edge of the tie and the shirt. In other words, the eye 7 can conveniently accommodate more 100 than the flat shirt and tie in that if both the shirt and tie should become ruffled at the edge there is sufficient space in the eye to accommodate this ruffling or increase of 105 thicknesses of the tie and shirt incident to the ruffling.

What is claimed is:—

A necktie holder comprising a pair of clasping members formed of a single piece of material bent intermediate its ends providing a yieldable hinge connection for the clasp members at one end, which hinge con-

nection also forms a finger piece, each clasp member including spaced portions each connected by bight portions at their ends opposite to their hinged ends, one clasp member 5 being narrower and longer than the other clasp member and extending over and beyond said bight portion of the other clasp member, the spaced portions of one clasp member having portions extending trans- 10 versely beyond the plane of the adjacent spaced portions of the other clasp member

and forming spaced oppositely disposed clamping points intermediate the ends of the clasp member to clasp the tie between said spaced points and the adjacent spaced 15 portions of the other clasp member.

In testimony whereof I affix my signature in presence of two witnesses.

STANLEY L. GEDNEY.
